UNITED STATES PATENT OFFICE.

WILLIAM LODGE AND NICHOLAS D. CHARD, OF CINCINNATI, OHIO, AS
SIGNORS TO THE LODGE & SHIPLEY MACHINE TOOL COMPANY, OF
CINCINNATI, OHIO, A CORPORATION.

APRON FOR LATHES.

SPECIFICATION forming part of Letters Patent No. 762,482, dated June 14, 1904.

Application filed July 28, 1903. Serial No. 167,367. (No model.)

To all whom it may concern:

Be it known that we, WILLIAM LODGE and NICHOLAS D. CHARD, citizens of the United States, residing at Cincinnati, in the county of Hamilton and State of Ohio, have invented certain new and useful Improvements in Aprons for Lathes, of which the following is a specification.

Our invention relates to an improved carriage-feed for engine-lathes.

The features of our invention are more fully set forth in the description of the accompanying drawings, making a part of this specification, in which:

15 Figure 1 is a front elevation of our improved carriage and apron in position upon the bed of the lathe. Fig. 2 is a reverse view of the reverse side of the mechanism mounted upon the apron. Fig. 3 is a section on line $\pi\pi$, Fig. 2, illustrating the main power driving means. Fig. 4 is a section on line $\nu\nu$, Fig. 2, showing the means for rapid return of the carriage. Fig. 5 is a section on line $\omega\omega$, Fig. 2, illustrating the carriage-feed. Fig. 6 is an end view of a portion of the apron-carriage with the automatic stopping mechanism in position. Fig. 7 is a detail view of the cam for operating the lever for automatically stopping the travel of the carriage. Fig. 8 is a horizontal section through a portion of the apron and the levers and rock-shafts for controlling the slow feed and high speed. Figs. 9 and 10 are sections on line $\varepsilon\varepsilon$, Fig. 8, illustrating the interlocking device between the slow-feed 35 and high-speed levers.

1 represents the lathe-bed, on the ways of which is mounted the usual carriage 2, said carriage having the usual apron 3.

4 represents a stationary screw suspended 40 along the lathe-bed, and it is upon this stationary screw that the carriage-feeding devices rotate to feed the carriage.

5 represents the feed-shaft of the lathe, driven from the head-stock by any suitable 45 mechanism.

The details of the first portion of the feeding device are best seen in Fig. 3, in which 6 represents a clutch keyed to the shaft 5 and

sliding thereon. 7 represents a sleeve loose on shaft 5. 8 represents the other clutch member, keyed on sleeve 7 and journaled in the apron-bracket 9. 10 represents a second sleeve keyed on sleeve 7, adapted to slide thereon and provided with right and left hand bevel-gears 11 and 12. Sleeve 10 is journaled in the apron-bracket 13 and provided with the yoke 14 for shifting said sleeve. Clutch 6 has the yoke 15 for shifting the clutch member 6 on the shaft 5. 16 represents a spur-gear having a sleeve-hub 17 journaled on the stub-shaft 18. 19 represents a bevel gear-wheel fixed on the sleeve 17 and adapted to be intermeshed by either of gear-wheels 11 or 12 as the sleeve 10 is shifted either to the right or left.

The levers for operating the clutch and reversing-gears are shown in Figs. 1 and 2, in which 21 represents a hand-lever fixed to the rock-shaft 21', the inner end of which shaft has a rock-arm 21*, which engages yoke 15 on the inside of the apron for shifting the clutch 6 and throwing in and out the main drive. 20 represents a hand-lever fixed to the rock-shaft 20'. (See Fig. 8.) The inner end of said shaft on the inside of the apron 75 has a rock-arm 20*, which engages the yoke 14 of the sleeve 10 for shifting gear-wheels 11 and 12 into and out of mesh with bevel gear-wheel 19. Gear-wheel 16 meshes with the spur gear-wheel 22, which is journaled in 80 the apron. (See Fig. 1.) Gear-wheel 22 has a sleeve on which is formed the bevel-gear 23. (See Fig. 5.) 24 represents a journal-bracket in the apron, in which is journaled the sleeve-nut 25, engaging the threads of the stationary 85 screw-rod 4. 26 represents a collar for holding the sleeve 25 in place. Sleeve 25 is provided at one end with the bevel gear-wheel 27, which meshes with the gear-wheel 23. Gear-wheels 22 and 23 are fixed to revolve together 90 on a stud-shaft 28, as shown in Fig. 5. Obviously as the drive is controlled by levers 20 and 21 the sleeve-nut 25 may be caused to revolve in either direction on the screw-rod 4, thus propelling the carriage in either direction.

95

We have provided an automatic trip for throwing out the carriage-feed, the details (see Figs. 1, 6, and 7) of which are as follows: 29 represents an adjustable stop mounted on 5 the carriage-ways of the bed and having a cam-like projection. (See Fig. 1.) 30 represents a trip or rock-shaft journaled in the carriage-bracket 31, so as to oscillate therein. 32 represents a coil-spring, one end of which 10 is attached to the bracket 31, the other end to a collar on shaft 30, so as to return the shaft to normal position whenever it is tripped for stopping the carriage. Shaft 30 is provided at each end with a radial tripping-arm 33, fixed to shaft 30 and provided at its outer end with a journal-pin 34, carrying the antifriction-roller 35, adapted to ride the cam of the bracket 29. It is to be understood that these pins 34 are journaled within the apron, so as 15 to be moved longitudinally in their bearings. As shown in Fig. 6, one end of said pin 34 carries the roller 35 on the inside of the apron, the other end of the pin 34 being on the outside of the apron and engaging the end of the 20 rocking arm 33. The shaft 30 is provided with a sleeve 36, having a cam-block 37 and engaging an antifrictional roller 38, journaled on a pin on the inside of the lever 21, as shown in Figs. 1, 6, 7. When the roller 35 25 encounters the bracket 29 in its adjusted position, it is pushed out, rocking the arm 33, the shaft 30, and the sleeve 36, thereby causing the cam 37 to push out the roller 38 and moving lever 21 to disengage the 30 clutch 6. In order to accelerate this movement of the lever 21 and to disengage the teeth of the clutch members 6 and 8 in a quick throw, we provide the following devices: 39 represents a taper pin having a bevel point, said 35 40 pin being fixed in the apron 3, as shown in Fig. 3. The lever 21 is provided with a corresponding taper pin 40, having a stem 41, moving in and out in a screw-cap 42, engaging the lever 21. 43 represents a coil-spring 45 between the inner end of the taper pin 40 and the inner end of the cap 42. Pins 39 and 40 are so placed that as the lever 21 is manipulated they intercept, and then pin 40 is deflected. When the points of pins 39 and 40 pass each 50 other, the spring 43 forces away the pin 40, thus imparting to the lever 21 a quick throw, which effects an instantaneous disengagement of the teeth of clutch members 6 and 8, thereby minimizing the wear and breakage which 55 would result from a slow engagement and disengagement of the clutch-teeth. It is obvious that by the use of two adjustable brackets 29, one at each end of the carriage, the carriage can be automatically stopped in 60 either direction of its travel.

We have provided the following devices for imparting a high speed to the carriage in either direction. 44 represents a high-speed shaft suspended along the lathe-bed and suitably driven from the head-stock or from the

counter-shaft. The details of this mechanism are best seen in Figs. 1, 2, and 4. 45 represents a sleeve keyed on shaft 44, so as to slide thereon, and provided with a bevel friction-clutch disk or cup 46 at each end. 47 represents sleeves journaled in the apron-bearing bracket 48 and having the friction-clutch disk or cups 49 co-operating with the adjacent cups 46. Sleeves 47 are provided with the bevel gear-wheels 50, which are always in 75 mesh with the intermediate transversely-journaled bevel gear-wheel 51. Bevel gear-wheel 51 is fixed on the sleeve of the spur gear-wheel 52, which spur gear-wheel and its sleeve are journaled on the journal-pin 54. (See 80 Fig. 4.) Disk 46 is provided with a yoke 54 for shifting the clutch members 46 in either direction on shaft 44.

Looking at Fig. 1, 55 represents a hand-wheel fixed on the stud-shaft 56, to which is also 85 fixed, on the inside of the apron, a gear 57 and engaging with the gear-wheel 22 for propelling the carriage by hand. The spur gear-wheel 57 also meshes with this gear-wheel for imparting fast speed in either direction to 90 the carriage. 58 represents a hand-lever fixed to the rock-shaft 58'. (See Fig. 8.) Rock-shaft 58' has a rock-arm 58" on the inside of the apron, which engages with the yoke 54 on shaft 44. It is obvious that as the hand-lever 58 is thrown in either direction either of the bevel gear-wheels 50 are fixed to turn with the shaft 44, depending upon which of the frictional members 46 is in an engagement with its co-operating frictional member 49. 95 In order to prevent the slow feed and the high speed from being thrown in at the same time, we provide the locking-bar 59. (Shown in Fig. 1, also Figs. 8, 9, and 10.) This locking-bar slides in the journal-brackets 60 on 105 the outside of the apron. The levers 20 and 58 are provided with locking-detents 61, into which the opposite ends of the locking-bar 59 alternately engage. If the locking-bar 59 be thrown in reverse direction to free the lever 110 58, so that the high speed may be availed of, the other end of the bar 59 engages the lever 20 and locks the slow feed out of commission.

The details of the interlock between levers 20 and 58 are more fully shown in Figs. 8, 9, 115 and 10. In Fig. 10 both levers are in idle position, lever 58 being locked in idle position by rod 59 engaging the detent 61 of lever 58, which leaves lever 20 free to be thrown in either direction for a direct or reverse 120 feed. In Fig. 9 the lever 20 has been moved to one position, and the fulcrum end of lever 20, engaging the end of the rod 59, prevents the rod 59 from being shifted, and so locks the lever 58 in idle position. With the parts 125 as shown in Fig. 10 if rod 59 be shifted to engage the detent 61 in lever 20 lever 58 may be thrown in either direction and lever 20 will be locked out of commission except when lever 58 is in the intermediate or idle position. 130

This feed mechanism, which we have described in detail, gives every facility to the carriage movement with the fewest possible parts and with a controlling-lock, whereby 5 those different devices are necessarily employed independently.

In Fig. 1 the locking-bar is shown engaging lever 58, so that the fast feed cannot be employed, and having the lever 20 free for operating the reversing-gears of the regular feed.

Having described our invention, we claim—

1. In a carriage-feed, a feed-shaft, transmitting devices thereon for propelling the carriage, a clutch between said feed-shaft and 15 said transmitting devices, a lever for throwing said clutch, an adjustable bracket on the lathe-bed, a rock-shaft journaled on the outside of the apron, having a radial arm, a push-pin journaled in the carriage, one end of 20 which engages the said radial arm, the other end being adapted to be engaged and deflected by said bracket, a trip-cam on said rock-shaft adapted to engage the said clutch-lever and trip the same when the carriage meets the 25 adjustable bracket, substantially as described.

2. In a carriage-feed, a slow-feed shaft and a high-speed shaft, transmitting devices comprising reversing gear-wheels on the slow-feed shaft for propelling the carriage, means for 30 throwing into operation or idle position said gear-wheels, transmitting devices comprising reversing gear-wheels on the high-speed shaft for propelling the carriage, means for throwing 35 said gears into operation or idle position, and a locking device between the two sets of transmitting devices, whereby they are alternately locked and released, substantially as described.

3. In a carriage-feed, a stationary screw-rod, a slow-feed shaft and a high-speed shaft, one set of transmitting devices comprising reversing gear-wheels between the slow-feed shaft and the screw-rod, means for throwing 45 said gear-wheels into train or into idle position, a second set of transmitting devices comprising reversing gear-wheels between the high-speed shaft and the screw-rod, means for throwing said gear-wheels into train or into idle position, levers for controlling the two 50 independent sets of reversing gear-wheels, and a locking-bar between said levers, adapted to lock one lever in engaging position

while the other is in idle position, substantially as described.

4. In a carriage-feed, a stationary screw-rod, a slow-feed shaft and a high-speed shaft, a sleeve-nut on the screw-rod, transmitting devices including reversing gear-wheels between the said sleeve-nut and the slow-feed shaft, a lever for controlling said reversing gear-wheels, transmitting devices including reversing gear-wheels between the high-speed shaft and the said sleeve-nut, a lever for controlling 60 said reversing gear-wheels, a locking-bar movably mounted between the said two levers, the 65 said levers being provided with detents adapted to be alternately engaged by the opposite ends of said locking-bar when it is shifted in opposite directions whereby the said slow feed and high speed are independently available, 70 substantially as described.

5. In a carriage-feed, a slow-feed shaft and a high-speed shaft, independent sets of transmitting devices, on each of said shafts for propelling the carriage, levers for independently controlling said transmitting devices, and a locking device between the said levers adapted to lock one lever when the other lever is released and vice versa, whereby said 75 slow feed and high speed can only be used independently, substantially as described.

6. In a carriage-feed, comprising two sets of transmitting devices, for independently propelling the carriage, levers for throwing either of the sets of transmitting devices into train 80 or idle position, a shifting lock-bar supported between said levers, the said levers being provided with detents opposed when both of said levers are in idle position, and adapted to be alternately engaged by said lock-bar, said levers 85 each having a bearing-surface adapted to be alternately opposed to opposite ends of said lock-bar, whereby said bar can only be shifted from one detent to the other, when the levers are both in idle position, substantially as described.

In testimony whereof we have hereunto set our hands.

WILLIAM LODGE.
NICHOLAS D. CHARD.
